UNITED STATES PATENT OFFICE.

HOWARD T. HALLOWELL, OF PHILADELPHIA, PENNSYLVANIA.

SHAFT-HANGER.

1,309,729.

Specification of Letters Patent. Patented July 15, 1919.

Application filed August 21, 1915. Serial No. 46,689.

To all whom it may concern:

Be it known that I, HOWARD T. HALLOWELL, a citizen of the United States, residing in Philadelphia, Pennsylvania, have invented certain Improvements in Shaft-Hangers, of which the following is a specification.

My invention relates to shaft supporting elements familiarly known as "hangers," and it consists of certain improvements in pressed sheet metal structures whereby I am enabled to produce highly satisfactory articles from relatively thin metal sheets.

My present invention relates more particularly to a compound structure in which I provide a hanger having sheet metal legs with separate, attached feet, which feet may be of a plurality of layers of sheet metal, or of heavier sheet metal, or of cast metal, of the necessary shape, which feet are firmly secured to the legs by rivets, bolts or the like. My improved structure in its finished form substantially follows the lines of the structure disclosed and claimed in the application before referred to, in which the leg and foot are integral.

These and other features of my invention are more fully described hereinafter, reference being had to the accompanying drawings, in which:

Figure 1, is an elevation, partly in section, of a shaft hanger embodying my present improvements;

Figs. 2 and 3, are elevations at right angles to each other of one of the legs before assembly;

Fig. 4, is a sectional plan view on the line IV—IV, Fig. 1;

Fig. 5, is an inverted plan view illustrating a modification;

Figs. 6 and 7, are views of details of my improved structure;

Figs. 8, 9, 10 and 11, are views illustrating various forms of separate feet to which the improved sheet metal legs forming the subject of my invention may be attached, and

Figs. 12, 13, 14 and 15, are views of different forms of legs which may be employed in my present construction.

As in the application before referred to, the pressed sheet metal legs of my present hanger, indicated at 1, have substantially centrally disposed longitudinal ribs 2 extending throughout their length; the lower ends of said legs terminating in channel portions 3 generally rectangular and sub-

stantially U-shape in cross section, the side walls of which channels are reinforced by inturning a portion 3a of the sheet metal of the leg upon itself. The legs may be provided with inwardly disposed rolled or beaded edges 4 extending throughout their length, and in the fabrication of the complete hanger said legs are preferably connected together at their lower ends by a suitable cross-piece 6, which may be cradle-shaped, as indicated. This cross piece may be secured to said channeled lower ends 3 by the bolts 7, indicated in Fig. 1. In addition, the legs are connected together at a substantially central point by a cross piece 8, which cross piece may comprise a double-walled structure having top and side webs 9 and 10, with flaring ends which fit under the beaded edges 4 of the legs.

This construction being identical or substantially so with the structure illustrated in my pending application before referred to, no particular description thereof herein seems to be necessary, since no claim is made to the same. The manner of making the leg portion of the structure of my present invention is substantially identical with that disclosed in my pending application; hence no particular reference to the same need be made.

The hanger leg is provided with an inner cover plate 15 to give the structure a finish, and such plate may have a central strengthening rib, as b, with outturned beaded or rounded edges b' which may be engaged by the inturned rolled or beaded edges of the leg in its finished condition.

In my present structure, the sheet metal leg is cut off at the point x at a point convenient for the attachment of the foot of the same, and the necessary foot is provided by a cast metal structure 20, more clearly illustrated in Figs. 8 and 9. This cast metal structure preferably has what might be termed a depending portion 22 which lies within or between the inner and outer walls of the hanger leg when the cover plate 15 is employed, and the foot portion proper, indicated at 23, is provided with the usual bolt aperture 24 for attachment to a supporting structure.

The depending portion of the foot section is preferably provided with a rib 25 which fits within the walls of the longitudinal rib 2 of the leg, and said foot may be secured to the leg by means of rivets 26 which pass

through the walls of the plates adjacent the side edges of the leg, and by rivets 27 which pass through the ribs 2 and 25.

It will be understood, of course, that these 5 feet may be of various forms, see Figs. 10 and 11, for instance, and of sheet metal or of cast metal, and that in some cases the rib 25 may be omitted. If desired, the inner cover plate may extend over the top of the 10 foot as indicated by dotted lines in Fig. 1.

I preferably connect the upper ends of the legs where they join the feet by means of a channel bar 30, preferably of pressed sheet metal, having integral ears 31 extending 15 outwardly therefrom, and lying substantially at right angles to the side walls of said channel member; which ears may be secured to the legs or the feet by the rivets holding the legs and feet together, as clearly 20 illustrated in Fig. 1. This channel bar connector is of a character substantially identical with the structure shown in the prior application, and hence no extended reference need be made thereto herein.

25 While I have shown my improved hanger leg as provided with a separate foot, which may be cast or otherwise prepared and secured inside the body of the same as shown in Fig. 1, it will be understood that such 30 separate foot may be disposed outside the hanger leg and secured thereto, and that in some instances, with either arrangement, the inner cover plate 15 may be omitted.

In Figs. 12, 13, 14 and 15, I have shown 35 cross sections of various forms of legs which I may employ, and with which the feet may be arranged inside or outside the same as desired; the feet being indicated by broken lines.

40 In Fig. 12, the leg is shown with outwardly disposed flanges or reinforcements 35 substantially at right angles to the body of the leg; the foot being disposed inside the leg.

45 In Fig. 13, I have shown a form of leg which omits the flanged or beaded edge; the foot being disposed inside the same.

In Fig. 14, I have shown a leg section 50 with beaded edges 36 inturned substantially 55 upon the flat portion of the metal; the foot portion being disposed between such beaded portions. If desired, this foot portion may extend under the beaded edge, and in some instances it may be grooved to receive the edge of the beaded portion.

In Fig. 15, I have shown the form of leg section illustrated in Fig. 12, with the foot disposed outside the same.

The shaft hanger structure with attached 60 feet as made in accordance with my present invention is neat in appearance; being substantially like the structure having the feet integral with the legs, and there is some 65 advantage in my present construction by reason of the fact that it avoids the neces-

sity of bending the upper end of the multiple plate leg structure to form the desired feet whereby the structure may be mounted in its proper position.

As this application possesses matter in 70 common with an application filed by me March 26, 1913, Serial No. 756,926, it is to be treated as a continuation of said prior application as far as the common subject-matter is concerned. 75

I claim:

1. In a shaft hanger, a leg of pressed sheet metal, a separate foot therefor having a portion disposed on the inside of said leg and another portion overlying the upper 80 end of said leg; said leg having continuous beaded edges and a longitudinal hollow reinforcing rib intermediate said beaded edges, and the foot having a rib on its portion adjacent the leg fitting the hollow reinforcing rib of the latter, and unitary means for connecting said leg and foot together. 85

2. In a shaft hanger, a leg of pressed sheet metal, a cast metal foot therefor of L-shape 90 having a portion overlying the upper end of said leg; said leg having continuous beaded edges and a longitudinal hollow reinforcing rib intermediate said beaded edges, and the foot having a rib fitting the 95 hollow reinforcing rib of the leg, a cover plate for the foot confined by the beaded edges, and unitary means for securing said leg, foot and cover plate together.

3. In a shaft hanger, a pair of legs of 100 pressed sheet metal, cast metal feet therefor, each having a portion overlying the upper end of a leg; said legs having continuous beaded edges and each having a longitudinal hollow reinforcing rib intermediate 105 said beaded edges and each foot having a rib fitting the hollow reinforcing rib of the leg, cover plates for said feet, a channeled connecting member disposed between the legs, and unitary means for securing 110 said legs, feet, cover plates, and connecting member together.

4. In a shaft hanger, the combination of a pressed sheet metal leg, a metal foot having a substantially horizontal portion overlying 115 said leg and a depending portion engaging the upper portion of said leg, a cover plate between which and the wall of the leg the depending portion of the foot is confined, and means for securing said cover 120 plate, foot, and leg together.

5. In a shaft hanger, the combination of a pressed sheet metal leg, a cast metal foot having a substantially horizontal portion 125 overlying said leg and a depending portion engaging the upper portion of said leg, a cover plate between which and the wall of the leg the depending portion of the foot is confined, and means for securing said cover plate, foot, and leg together. 130

6. In a shaft hanger, the combination of a pair of pressed sheet metal legs, a pair of cast metal feet of L-shape for engagement with the respective legs; each foot having a 5 substantially vertical portion engaging the side of the leg and a portion overlying the upper end of the leg to which it is attached, covering plates for said feet, and unitary means for securing said legs, feet and cover 10 plates together.

7. In a shaft hanger, the combination of a pair of pressed sheet metal legs, each having a longitudinal hollow reinforcing rib,

a pair of cast metal feet for connection with the respective legs; each foot having a portion overlying the upper end of the leg to which it is attached and a ribbed portion engaging the rib of the leg, a channeled connecting member between said legs and disposed adjacent the feet thereof, and unitary means for securing said legs, feet, and channeled connecting member together. 15 20

HOWARD T. HALLOWELL.
